UNITED STATES PATENT OFFICE

165,842

MEDAL

Nathan Holz, Long Island City, N. Y.

Application August 12, 1948, Serial No. 148,079

Term of patent 14 years

(Cl. D29—2)

To all whom it may concern:

Be it known that I, Nathan Holz, a citizen of the United States residing at Long Island City, in the county of Queens and State of New York, have invented a new, original, and ornamental Design for a Medal of which the following is a specification, reference being had to the accompanying drawing, forming part hereof.

Fig. 1 is a top plan view of a medal showing my new design.

Fig. 2 is an edge view thereof.

I claim:

The ornamental design for a medal, as shown.

NATHAN HOLZ.
